US0D1028905S

(12) **United States Design Patent** (10) **Patent No.:** **US D1,028,905 S**
(45) **Date of Patent:** **** May 28, 2024**

(54) **CONTACTOR**

- (71) Applicant: **Schneider Electric Industries SAS**, Rueil-Malmaison (FR)
- (72) Inventors: **Yingzhi Guan**, Shanghai (CN); **Benoit Lecoanet**, Rueil-Malmaison (FR); **Leihong Zheng**, Shanghai (CN); **Min Xu**, Shanghai (CN); **Chuanwu Li**, Shanghai (CN); **Xu Han**, Shanghai (CN); **Zhibao Wang**, Shanghai (CN); **Hui Li**, Shanghai (CN)
- (73) Assignee: **Schneider Electric Industries SAS**, Rueil-Malmaison (FR)
- (**) Term: **15 Years**
- (21) Appl. No.: **29/853,362**
- (22) Filed: **Sep. 15, 2022**

CLAIM

The ornamental design for a contactor, as shown and described.

DESCRIPTION

FIG. 1 is a perspective view of contactor.

FIG. 2 is a front view of contactor.

FIG. 3 is a rear view of contactor.

FIG. 4 is a left side view of contactor.

FIG. 5 is a right side view of contactor.

FIG. 6 is a top plan view of contactor; and,

FIG. 7 is a bottom view of contactor.

The broken lines in the drawings illustrate portions of a contactor that form no part of the claimed design.

1 Claim, 7 Drawing Sheets
